UNITED STATES PATENT OFFICE.

EARLE H. WHEATON, OF NEW HAVEN, CONNECTICUT, ASSIGNOR TO UNDERWOOD
TYPEWRITER COMPANY, OF NEW YORK, N. Y., A CORPORATION OF DELAWARE.

TYPE-WRITING MACHINE.

1,302,460.

Specification of Letters Patent. Patented Apr. 29, 1919.

Application filed October 16, 1917. Serial No. 196,779.

To all whom it may concern:

Be it known that I, EARLE H. WHEATON, a citizen of the United States, residing in New Haven, in the county of New Haven and State of Connecticut, have invented certain new and useful Improvements in Type-Writing Machines, of which the following is a specification.

This invention relates to typewriting machines, and is especially adapted to be used in a front-strike typewriting machine, to enable work-sheets to be collated or adjusted relatively to one another at the position most convenient to the typist, namely, the front of the machine.

The invention is herein disclosed as applied to an Underwood typewriting machine. The platen is thrown up clear of the feed rolls, so that a work-sheet horizontally inserted may pass straight beneath the platen. The platen is thrown up rearwardly, thus providing ample space in which the typist may inspect and handle the work-sheets. The platen may normally tend to swing into its upper position, so that the typist may make ready the machine for the insertion of work-sheets by the mere release of a latch, which normally holds the platen down to coöperate with the feed rolls in holding the work-sheets.

There may be provided one or more gages in the form of impaling pins mounted on the front of the typewriter carriage, to coöperate with perforations in the work-sheets. The gage or pin may be located where it will not interfere with the manipulation of work-sheets in the ordinary manner in a typewriting machine.

The sheets one by one are laid face down upon a table or rest at the front of the carriage, with their rear portions extending under the platen. The sheets are collated in various relationships by means of the collating pins which rise from said table, to engage holes punched in the side margins of the sheets. Usually one pin at each side of the table will be sufficient. After the sheets are collated, and while they remain engaged by the pins, the platen is swung down to printing position, carrying down with it the rear portions of the sheets, until the latter are gripped between the platen and the usual bottom feed rolls. The sheets are thus always under control, and may now be released from the pins.

Other features and advantages will hereinafter appear.

In the accompanying drawings, Figure 1 is a plan view of part of an Underwood typewriting machine, showing my invention as applied thereto.

Fig. 2 is a sectional end view thereof, the section being taken along the line 2—2 of Fig. 1.

Fig. 3 is a view similar to Fig. 2, the section, however, being partly taken nearer the center of the machine, and the platen being thrown up to enable a work-sheet, shown therein, to be adjusted on the collating pins.

Fig. 4 is a diagrammatic perspective view, showing a work-sheet adjusted on the platen.

Fig. 5 is a diagrammatic plan view, showing how a plurality of work-sheets may be adjusted.

The usual Underwood typewriting machine is provided with rails 1 and 2 on which slides the carriage frame 3, said frame forming a mounting for the platen 4, which platen is adapted to be rotated by the usual line-space lever 5 effective on the usual slide 6.

As shown in Figs. 1, 2 and 3, the platen is mounted on stub shafts 7 and 8, which are journaled in a swing frame, which includes end plates 9 and 10 and a tie-rod 11. This frame is journaled in the usual shift frame 12 on stub shafts 13 and 14, so that the platen may be swung from the lower position (Fig. 2), in which it bears against the feed rolls 15 and 16, into the upper position, seen in Fig. 3, in which latter position a work-sheet 17 is adapted to be passed horizontally beneath the platen.

When the platen 4 is swung up to the Fig. 3 position, one or more work-sheets 17 may be adjusted on a vertical pin 18, which is mounted on a work-adjusting table in the form of a plate 19 fast to the frame of the carriage, said pin being placed well inwardly from the frame so as to bring the pin as close to the printing line as may be without bringing the pin into a position where it will be awkward to adjust a work-sheet thereon.

As shown in Fig. 3, the work-sheet 17, when impaled on the pin 18, will extend nearly horizontally rearwardly so that the farther end 20 thereof, which is the lower end of the work-sheet, may reach toward and even beyond the usual paper table 21, rest-

ing on the rear end thereof, as shown in Fig. 3. To enable work-sheets to be accurately adjusted, there may be provided a margin gage, which may take the form of a 5 second pin 22 alined with the pin 18.

After the work-sheet 17 has been adjusted to the desired printing line, the platen 4 is swung downwardly by drawing on a handle 23 formed as an extension of the side plate 10, and the platen may be caught in this 10 lower position by a spring-actuated catch 24, which is adapted to catch over a pin 25 mounted on said side plate 10. When thus drawn down, the platen 4 holds the work-sheet against the usual feed rolls 15 and 16. During the operation of drawing down the 15 platen from its Fig. 3 position, the typist may hold the work-sheet in position by placing a thumb or finger upon the plate 19. To 20 do this most conveniently, the handle 23 is placed at the right-hand side of the machine to be manipulated by the right hand, and the thumb or finger of the left hand may hold the work-sheet.

After the platen has gripped the work-sheet against the feed rolls, the typist may 25 remove the finger or thumb from the plate 19, thus permitting the work-sheet to assume an upright position where it may be detained by a bar 26. This bar is mounted 30 near the platen and made fast in the plate 19 and supported at its right-hand end in an extension 27 of the plate 19, the bar 26 being so positioned that it is above the usual 35 type guide 28 into which the type-bars 29 (Fig. 4) strike, and also above the wing scales 30, with the result that the bar 26 protects both the wing scales and the ribbon vibrator (not shown), which is adjacent 40 the type guide 28, in such a way that even if the work-sheet is stiff, it will not injure the wing scales or ribbon vibrator by tending to bend them.

In order that the bar may obstruct the 45 view of the work-sheet as little as possible after being written upon, the bar 26 is made as small as is consistent with the necessary strength, and may be in the form of a heavy wire having reduced ends 31, which are engaged by the turned-up ends 32 of the plate 50 19 and of the extension 27.

The pin 18 is advantageously placed well 55 within the carriage on a horizontal portion of the plate 19 near the point at which said plate bends down rapidly toward the bar 26. The plate 19 may be integral with the extension 27 and may carry near the front edge thereof the margin gage or second adjusting pin 22.

In order to accommodate work-sheets, 60 which are to be alined at the right-hand side of the machine, or on which the perforations are not adapted to aline with both of the pins 18 and 22, there may be provided a pin 65 or pins 33 and 34 on the extension 27 alined

with the pins 18 and 22, and these pins 33, 34 may serve either as impaling pins or as margin gages. For removing or adjusting work-sheets, the feed rolls 15 and 16 may be provided with the usual casting-off mechanism 70 35.

To rotate the platen, there may be provided the usual knobs 36, which, in the present invention, are usually mounted on stub shafts 37, and to enable both the knobs 36 75 and the line-space lever 5 to always have the platen under control, the platen may be constantly geared thereto by mechanism somewhat analogous to the mechanism of the usual fan-fold typewriting machines. For 80 this purpose, a stub shaft 37, which is connected both to a knob 36 and to the line-space mechanism, is provided with a gear wheel 38 constantly in mesh with an idle pinion 39 journaled on the stub shaft 14, 85 and the platen shaft 7 is provided with a gear wheel 41 which is also constantly in mesh with the idle pinion 39. The connections, therefore, are such that as the platen swings up and down in its swing frame, 90 the side plates thereof always hold the pinions 38, 39 and 41 in mesh with each other, thus keeping the platen always under the control of the rotating mechanism.

At the opposite end of the carriage a 95 similar idle pinion 42 may mesh with a gear wheel 43 fast to the platen shaft 8 and with a gear wheel 44 fast to the usual other knob (not shown), thus preserving the symmetry of construction which conduces to the 100 accuracy of the machine.

To facilitate the operative in rapidly adjusting and removing work-sheets, the platen swing frame is adapted to be swung 105 up vertically and automatically by means of a spring 45, which bears against the side plate 10, and may be coiled around the stub shaft 13 and anchored against a pin 46 in the platen shift frame.

In order to prevent the platen from being thrown too far over, the side plate 10 may be extended rearwardly at 47, forming an extension which strikes against the pin 46 to limit the throw of the swing frame. The catch 24 may be operated by a finger-piece 48, which is conveniently located at the right-hand of the machine, and cooperates with a stop 48a to hold the catch against overthrow when released from the swing frame.

By having the pin or pins 18, 22, 33 and 34 mounted on the typewriter carriage it is possible to locate work-sheets on the platen, whatever the position of the typewriter carriage may be along the usual 125 scale plate 49. This makes it possible to utilize the bent portion 50 of the plate 19 as a rest for the finger and as a curve to guide the work-sheet when it is being bent downwardly under the pressure of the platen, 130

thus avoiding any tendency to form a sharp bend or ridge over the bar 26, with the result that the work-sheet will bend in the manner shown in Fig. 4.

- 5 The pin or pins 18 and 22 may be utilized as shown in Fig. 5, wherein a work-sheet 51 may be alined accurately thereby, and, if desired, other work-sheets 52 and 53 may be alined relatively thereto by impaling on 10 the other pin or pins 33 and 34. By having pins at both sides of the machine it becomes possible to collate work-sheets extending only part way across as is shown in said Fig. 5, the sheet 51 extending only 15 part way from the left, and the sheet 52 extending only part way from the right. It is possible for the typist to hold both these sheets against slipping while the platen is swinging down by resting the fingers of one 20 or both hands on the upper part of the plate 19.

In order to enable the work-sheets to be rapidly and accurately adjusted without the need of the typist turning them over 25 to inspect them, the lines on which writing is to be done below the usual cross rulings 54, may be numbered as shown at 55, and the perforations may be correspondingly numbered on the back of the sheet, as shown 30 at 56. It will be noted that the numberings 55 do not coincide with the numberings 56. The numberings on the back of the sheet are so placed that when a given numbering is at the pin 18, the corresponding numbering 35 55 on the front of the sheet will be at the printing point when the platen is swung to its home position where the type 29 will write on the face thereof.

The work-sheet shown in Fig. 4 is also 40 shown provided with the usual rulings 57, but the typist need pay no visual attention to the adjustment of said rulings with reference to the scales on the wing scales of the typewriter, if the machine is properly 45 adjusted, and the perforations 58 of the work-sheet are properly adjusted with reference thereto, since such proper adjustment brings it about that the impaling of a sheet on the pin 18 will bring the rulings on the face 50 of the sheet in proper relations to the scales and escapement mechanism of the typewriter.

The usual knob 59 on which the pointer 60 is mounted is preferably cut down to a level with the top of the plate 19, thus permitting a work-sheet to lie smoothly on said table.

Variations may be resorted to within the scope of the invention, and portions of the improvements may be used without others.

Having thus described my invention, I claim:

1. In a machine of the class described, the combination with a rotating platen, of a traveling carriage in which said platen is

70 journaled, feed rolls adapted to coöperate with said platen to hold a work-sheet, means for swinging said platen away from said feed rolls to permit the work-sheet to be inserted therebetween, and collating guides adjacent the front of said carriage adapted to serve as guides to enable the typist to adjust the work-sheet and then swing the platen into position against the feed rolls to hold the work-sheet. 75

2. In a machine of the class described, the combination with a rotating platen, of a traveling carriage in which said platen is journaled, feed rolls adapted to coöperate with said platen to hold a work-sheet, means 80 for swinging said platen away from said feed rolls to permit the work-sheet to be inserted therebetween, a bar extending along said platen adapted to guide the work-sheet toward the platen as the platen swings down 85 to its home position, and collating guides adjacent the front of said carriage adapted to serve as guides to enable the typist to adjust the work-sheet and then swing the platen into position against the feed rolls to hold 90 the work-sheet.

3. In a machine of the class described, the combination with a rotating platen, of a traveling carriage in which said platen is journaled, feed rolls adapted to coöperate 95 with said platen to hold a work-sheet, means for swinging said platen away from said feed rolls to permit the work-sheet to be inserted therebetween, a bar at the front of said carriage forming a work-table on which 100 sheets may be collated, a collating guide on said work-table on which sheets may be adjusted horizontally, a supporting device at the rear of the carriage to support the rear end of a sheet so adjusted, and a guiding device 105 for guiding the work-sheet as it is bent downwardly by bringing the platen against the feed rolls.

4. In a machine of the class described, the combination with a traveling typewriter carriage, of a platen journaled in said carriage, feed rolls against which said platen is adapted to hold work-sheets, means permitting the platen to be swung clear of the feed rolls to allow a work-sheet to be passed substantially horizontally beneath the platen, 115 a bar at the front of said carriage forming a table on which the work-sheet may be adjusted, a pin on said bar, and means adapted to coöperate with a work-sheet adjusted on said pin, to enable the operative to adjust the work-sheet accurately thereby. 120

5. In a machine of the class described, the combination with a traveling typewriter carriage, of a platen journaled in said carriage, feed rolls against which said platen is adapted to hold work-sheets, means permitting the platen to be swung clear of the feed rolls to allow a work-sheet to be passed substantially horizontally beneath the platen, a 130

bar at the front of said carriage forming a table on which the work-sheet may be adjusted, a pin on said bar, means adapted to coöperate with a work-sheet adjusted on said 5 pin to enable the operative to adjust a work-sheet accurately thereby, an extension of said table adapted to form a guide for the work-sheet as the platen is brought to position against the feed rolls, and a bar forming 10 part of said extension extending substantially along the entire face of the platen.

6. In a machine of the class described, the combination with a traveling typewriter carriage and a platen journaled therein, of feed 15 rolls adapted to coöperate with said platen to hold work-sheets, a paper table behind said platen adapted to support the end of work-sheets, means permitting the platen to be swung up clear of the feed rolls to permit 20 a work-sheet to be extended substantially horizontally beneath the platen, a bar at the front of the typewriter carriage forming a table for so adjusting a work-sheet, and collating pins on said bar adapted to cause 25 the operative to adjust a work-sheet accurately.

7. In a machine of the class described, the combination with a traveling typewriter carriage and a platen journaled therein, of feed 30 rolls adapted to coöperate with said platen to hold work-sheets, a paper table behind said platen adapted to support the end of a work-sheet, means permitting the platen to be swung up clear of the feed rolls to permit 35 a work-sheet to be extended substantially horizontally beneath the platen, a bar at the front of the typewriter carriage forming a table for so adjusting a work-sheet, collating pins on said bar adapted to cause the operative 40 to adjust the work-sheet accurately, and an extension of said work-table lying adjacent said platen and adapted to cause the work-sheet to bend smoothly as the platen is swung to position against the feed rolls.

45 8. In a machine of the class described, the combination with a traveling typewriter carriage, of a platen journaled therein, feed-rolls against which said platen is adapted to bear, means for rotating said platen, a 50 frame in which said platen is mounted and adapted to be displaced upwardly while still under the control of the rotating means, a work-table at the front of the platen upon which work-sheets may be adjusted while 55 lying thereon, and a pin upon which said sheets may be impaled, said pin so located that numbered writing lines on the face of the sheets may be brought to the printing point when correspondingly numbered perforations on the work-sheets are impaled upon said pin.

60 9. In a machine of the class described, the combination with a traveling typewriter carriage, of a platen journaled therein, feed-rolls against which said platen is adapt- 65

ed to bear to hold a work-sheet, a swinging frame in which said platen is journaled, a latch normally holding said platen against said feed rolls, a spring adapted to automatically swing said platen clear of 70 said feed rolls upon the release of said latch, a paper table behind said platen over which said platen swings, and a collating table in front of said platen upon which work-sheets are adapted to be collated by the typist. 75

10. In a machine of the class described, the combination with a traveling typewriter carriage, of a platen journaled therein, feed rolls against which said platen is adapted 80 to bear to hold a work-sheet, a swinging frame in which said platen is journaled, a latch normally holding said platen against said feed rolls, a spring adapted to automatically swing said platen clear of 85 said feed rolls upon the release of said latch, a paper table behind said platen over which said platen swings, a work-table in front of said platen, collating pins upon said table upon which the work-sheet is adapted to be 90 held as the platen is swung back into place, and a guide for holding the work-sheet as the platen is so swung.

11. In a machine of the class described, the combination with a traveling typewriter 95 carriage and a platen journaled therein, of feed rolls against which the platen is adapted to bear, means for rotating said platen, a swing frame in which said platen is mounted and adapted to be swung while 100 still under control of the rotating means, a paper table behind said platen, and a work-table at the front of said platen upon which a work-sheet is adapted to be adjusted while lying substantially horizontally thereon and 105 upon the end of said table.

12. In a machine of the class described, the combination with a traveling typewriter carriage, of a platen journaled therein, feed-rolls against which said platen bears, means 110 for rotating said platen, a frame in which said platen is mounted to be displaced upwardly while still under the control of the rotating means, a work-table at the front of the platen upon which work-sheets may be ad- 115 justed while lying substantially horizontally thereon, and a pin on each margin of the carriage upon which said work-sheets may be impaled, said pins so located that the numbered writing lines on the face of the sheets are brought to the printing point when correspondingly numbered perforations on the work-sheets are impaled upon 120 said pins.

13. In a machine of the class described, the combination with a traveling typewriter carriage, of a platen journaled therein, feed-rolls against which said platen bears, means 125 for rotating said platen, a frame in which said platen is mounted to be displaced up- 130

- wardly while still under the control of the rotating means, a work-table at the front of the platen upon which work-sheets may be adjusted while lying thereon, a pin on each margin of the carriage upon which work-sheets may be impaled, said pins so located that the numbered writing lines on the face of the sheets are brought to the printing point when correspondingly numbered 10 perforations on the work-sheets are impaled upon said pins, and devices coöperating with said pins for gaging work-sheets impaled thereon.
14. In a machine of the class described, 15 the combination with a traveling carriage including a frame, of a platen journaled in said carriage and adapted to be swung up therein, feed rolls against which said platen is adapted to bear when not swung up, a 20 collating table at the front of the carriage frame, extensions of said table extending toward said platen and including a gaging device, and a bar adjacent said platen supported by said extensions and forming a 25 guide about which a work-sheet may bend when the platen is moved against the feed rolls, said bar adapted to permit a largely unobstructed view of the work-sheet adjacent the writing line near the platen.
- 30 15. In a machine of the class described, the combination with a traveling carriage including a frame, of a platen journaled in said carriage and adapted to be swung up therein, feed rolls against which said platen 35 is adapted to bear when not swung up, a collating table at the front of the carriage frame, extensions of said table extending toward said platen and including a gaging device, a bar adjacent said platen supported 40 by said extensions and forming a guide about which a work-sheet may bend when the platen is moved against the feed rolls, said bar adapted to permit a largely unob- structed view of the work-sheet adjacent the writing line near the platen, a swing frame 45 in which said platen is journaled to permit it to be moved away from the feed rolls, a support at the rear of the platen adapted to support work-sheets, and means for supporting said swing frame to permit the 50 platen to swing upwardly and rearwardly to permit work-sheets to be adjusted thereunder.
16. In a machine of the class described, the combination with a traveling carriage 55 and a platen journaled therein, of a swing frame in which said platen swings in said carriage to permit work-sheets to be adjusted thereunder, a collating table forming the front of said carriage upon which work-sheets can be adjusted, and pins on each side of said table adapted to form guides for so adjusting the work-sheets.
17. In a typewriting machine, the combination with a revolute platen, of a carriage 65 upon which said platen is mounted, feed-rolls to run on the under side of the platen to hold the work-sheets, said platen being mounted for displacement up and away from said feed-rolls to permit the introduc- 70 tion of work-sheets beneath the platen, sup- porting means on said carriage in front of the platen upon which the forward ends of the work-sheets may rest as they extend back under the platen, and means also on 75 said carriage and in front of the platen for gaging the work-sheets in various relative positions and detaining them as they are carried downwardly at their rear portions by the platen and until they are gripped by 80 the platen against the feed-rolls.

EARLE H. WHEATON.
